COMBINED LABEL AND TIE HOLDER

Isadore D. Wolfson, New York, N. Y.

Application May 21, 1934, Serial No. 726,619

5 Claims.

(Cl. 2—145)

This invention relates to combined tie holders and tie labels and contemplates the provision of a flexible loop designed to be secured to the tie at the time it is made and provided with button holes for buttoning the loop to a shirt button.

It has been customary in making ties to sew a label thereto bearing the name of the maker or seller or bearing other indicia. The label has no function other than its function as a label.

My invention, however, also contemplates the provision of means combining the function of the label heretofore customarily used, with the function of a tie holder.

My invention further contemplates the provision of simple and inexpensive means for holding the tie on to the shirt of the wearer, which means is made a part of the tie at the time of its construction, and which does not interfere with the tying or knotting of the tie.

My invention further contemplates the provision of a combined tie holder and label which is not likely to become detached from the tie nor lost, as is possible with separate tie holding clips, and which is provided with integral means adapted to cooperate with a shirt button for securing the tie in place to the shirt.

My invention further contemplates the provision of a simple and inexpensive method of making the combined label and tie holder.

The various objects of my invention will be clear from the description which follows, and from the drawing, in which,

Fig. 1 is a front view of my invention as it appears in operation, connecting the tie to the shirt, the ends of the tie which normally conceal the holder being shown lifted to expose the holder.

Fig. 2 is a rear view of the wide end portion of a tie to which my improved holder has been attached.

Fig. 3 is a horizontal section of a tie showing how my improved holder may be secured in place between the flaps of a tie by hand stitching at the time the tie is made.

Fig. 4 is a similar section of a modified form of the same showing how the holder is secured in place at the flaps when the flaps are machine stitched in reverse or inside out position.

Fig. 5 is a similar section of the same, the tie having been turned into right side out position.

Fig. 6 is a similar section of a modified form of tie comprising two plies of material secured together at their edges, and showing how the holder is secured in place during the construction of the tie and by the stitching which forms the tie.

Fig. 7 is an elevational view of the same as the tie appears in its inside out position and before the flaps have been folded therefrom.

Fig. 8 is an elevational view of part of the continuous strip of material from which my improved holder may be made.

In that practical embodiment of my invention which I have illustrated by way of example, I prefer to make my improved holder from a continuous strip of material 10. Said strip is woven with selvages 11 and 12 at its edges and is provided with a series of longitudinally arranged button holes as 13, 14 and 15, preferably equally spaced throughout the length of the strip, and midway between the selvages. The button holes are preferably woven directly into the strip and when so woven, are provided on each of their edges with a suitable selvage as 31. It will be understood, however, that the button holes 13, 14 and 15 may be otherwise formed, or may be made after the strip 10 has been woven, and that the button holes may be made by hand or by the usual button hole machine if desired.

Between the button holes is woven the name or trade-mark 16 of the maker or seller of the tie and his address, or other indicia 17 in a manner which is well known in the art of weaving fabric labels and hence which need not be shown nor described in detail. It will be understood, however, that the indicia 16 and 17 may be imprinted, embroidered, embossed or otherwise impressed on the strip if desired. To form the tie holding loop 20, a sufficient length is cut from the strip 10 to include the desired number of button holes, preferably three in number. The strip thus cut is doubled over on itself to bring its ends together and thus to form a loop. Said loop is made of sufficient length to provide an opening therein large enough to permit the passage therethrough of the narrow end portion 21 of the knotted tie after the loop has been secured in place. I prefer to fold said strip so that one of the button holes as 14 becomes arranged at the middle of the loop, while the other button holes as 13 and 15 at the sides of the loop are spaced differently from the shirt of the wearer when the tie is being worn. This permits the use of a selected button hole to hold the tie with the desired tension on to the nearest shirt button 23.

To secure the loop 20 in place, I prefer to utilize part of the stitching used in making the tie. In that form of four-in-hand tie shown in Figs. 2 and 3, wherein the rear flaps 25 and 26 of the tie are overlapped on each other, the doubled ends 24 of the loop are inserted between the overlapping parts of the flaps and stitched thereto by means of the usual hand made slip stitch 27 which secures said flaps together. Said stitch is customarily used for the purpose of holding the edges of the tie flaps together and to hold the filler or padding 28 at the same time, but I utilize said stitch for securing the

ends 24 of the loop in place at the same time that the flaps 25 and 26 are joined and the filler or padding 28 is secured in place.

In Fig. 4, I have shown a tie, the flaps 25 and 26 of which are joined together by the machine stitching 29 while the tie is in its inside out position. In this form of my invention, the ends 24 of the loop are inserted between the flaps with the loop on the inside of the tie, and are secured in place by the machine stitching 29 at the same time that the flaps 25 and 26 are joined. When the tie is turned right side out into the position of Fig. 5, the loop 20 assumes the exposed position at the back of the tie indicated in Fig. 5.

As shown in Figs. 6 and 7, however, the tie may consist of an outer part as 32 of tie material and an inner part as 33 of lining material, which parts are sewed together at their edges, 20 as by suitable stitching 34, in their reversed or face to face positions. In this form of the tie, the doubled ends 24 of the loop are inserted between the layers of fabric and between the adjacent edges of the parts 32 and 33 with the loop lying between said parts and in the interior of the reversed tie (Fig. 7).

When the stitching 34 is made, said stitching catches the ends 24 of the loop and secures the loop in place. When the tie is turned right side out and has been folded and secured into the position shown in Fig. 6, then the loop 20 becomes exposed and is arranged in its proper operative position to be on the rear face of the tie.

It will be understood that in any case, the ends 24 of the loop are secured to the wide part of the tie intermediate the neck band and the wide end of the tie and preferably, some distance above said wide end and in position 40 wherein one of the button holes will receive a shirt button as 23. The precise position of the loop is however, immaterial provided that it is secured to the wide part of the tie and to the rear face thereof.

However said loop is preferably pressed flat against the rear face of the tie in horizontal position as shown in Fig. 2 at the same time that the tie is pressed. The loop thereby normally extends across the flaps 25 and 26 with the indicia 16 and 17 thereof visible to the observer so as to accomplish its function as a label. During the pressing operation, the label is creased or folded at its side edges with the ends 24 thereof arranged intermediate said side edges. 55 In this position of the loop, the button hole 14 may be raised or lowered or extended laterally a distance equal to substantially the entire length of the loop, thereby providing a wide range of adjustment to permit securing of the loop to the button 23 as indicated by the dotted lines of Fig. 2.

Nevertheless, the loop, by reason of its position, does not interfere with the tying or knotting of the tie.

After the tie has been put on by the wearer and knotted into the position shown in Fig. 1, the narrow end 21 of the tie is passed through the loop 20 and the loop brought toward the button 23 with the desired tension, whereafter 70 the button 23 is passed through the nearest button hole of the loop.

It will be seen that the loop 20 serves not

only as a convenient and efficient tie holder, but that said loop by reason of the indicia 16 and 17 woven thereinto serves also as a label for the tie, identifying the tie as to maker or seller, and that it may be manufactured and secured in place at considerably less cost than the cost of the labels now customarily used.

It will further be seen that the loop cannot be misplaced or lost, that it adequately prevents the tie from flapping about in the wind, and 10 that it is fully adequate to hold the tie in its proper position against the shirt.

While I have shown and described certain specific embodiments of my invention, I do not wish to be understood as limiting myself thereto but intend to claim my invention as broadly as may be permitted by the state of the prior art and the scope of the appended claims.

I claim:

1. The combination with a necktie provided with a pair of rearwardly extending flaps, of a fabric strip folded on itself to bring the ends thereof together, and stitching securing said ends to at least one of the flaps, said strip being provided with a button hole intermediate its edges, 20 and said strip being of sufficient length to permit the passage therethrough of the narrower end of the tie, said strip being adapted to be secured to the shirt of the wearer by fastening the button of the shirt in the button hole. 30

2. In a four-in-hand tie provided with rear flaps and with stitching joining said flaps, a loop bent from a woven strip of uniform width, said strip being provided with a selvage on each edge and with a longitudinally arranged button hole 35 intermediate the selvages, both of the ends of said strip being secured to the tie adjacent the edges of said rear flaps by said stitching, and said loop being laterally flattened.

3. In a four-in-hand tie, a loop formed of a narrow strip of woven material and secured with both of its ends together at the rear face of the tie by stitching forming part of the tie stitching, said loop being provided with a longitudinally arranged button hole intermediate its edges. 45

4. The combination with a tie having a pair of rear flaps joined by stitching, of an elongated strip of narrow, inelastic fabric, bent into the form of a flattened loop and having its ends secured together and also secured at the rear face of the wide portion of the tie at said stitching, said loop being laterally flattened by a pair of parallel preformed bends at the side extremities of the flattened loop, said strip being provided with a button hole midway between its ends for attachment to a shirt, and being of sufficient length to permit the passage therethrough of a narrow portion of the tie. 55

5. The method of making a tie holder comprising severing predetermined lengths from a strip having spaced button holes therein, folding the strip in half, bringing the ends of the strip together, stitching the ends of the folded strip in between the rear flaps of the wide part of a tie, spreading the strip laterally, and pressing and flattening the folded and stitched strip against the rear face of the tie to form a flattened loop extending equal distances on each side of the stitching to expose a button hole at the rear central part of the loop. 70
